(57) **CLAIM**

The ornamental design for a thermostat trim plate, as shown and described.

DESCRIPTION

FIG. 1 is a front, right, top perspective view of a thermostat trim plate according to a first embodiment of our new design;

FIG. 2 is a rear, left, top perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front, right, top perspective view of a thermostat trim plate according to a second embodiment of our new design;

FIG. 10 is a rear, left, top perspective view thereof;

FIG. 11 is a front view thereof;

FIG. 12 is a rear view thereof;

FIG. 13 is a top view thereof;

FIG. 14 is a bottom view thereof;

FIG. 15 is a right side view thereof;

FIG. 16 is a left side view thereof;

FIG. 17 is a front, right perspective view of a thermostat trim plate according to a third embodiment of our new design;

FIG. 18 is a rear, left perspective view thereof;

FIG. 19 is a front view thereof;

FIG. 20 is a rear view thereof;

FIG. 21 is a right side view thereof;

FIG. 22 is a left side view thereof;

FIG. 23 is a top view thereof; and,

FIG. 24 is a bottom view thereof.

The broken lines in FIGS. 9-12 illustrate parts of the thermostat trim plate that form no part of the claimed design. The shading in the figures indicate the character and contour of the surfaces represented, not to be confused with surface ornamentation.
